UNITED STATES PATENT OFFICE.

ROSS M. RUSSELL, OF BINGHAMTON, NEW YORK, ASSIGNOR TO THE KEYES-BAKER CIGAR ROLLING MACHINE COMPANY, OF SAME PLACE.

HEADER FOR CIGAR-BUNCH-ROLLING MACHINES.

SPECIFICATION forming part of Letters Patent No. 631,333, dated August 22, 1899.

Application filed December 10, 1897. Renewed April 20, 1899. Serial No. 713,753. (No model.)

To all whom it may concern:

Be it known that I, Ross M. RUSSELL, of Binghamton, in the county of Broome, in the State of New York, have invented new and useful Improvements in Headers for Cigar-Bunch-Rolling Machines, of which the following, taken in connection with the accompanying drawings, is a full, clear, and exact description.

10 My invention relates to cigar-bunch-rolling machines, and particularly to headers therefor.

15 My object is to provide such a machine with a sectional header, one section of which is stationary and the other is vertically reciprocated continuously to strike percussively upon the head of the rotating bunch, whereby the stock therein is compacted without twisting, smoothed exteriorly, and rounded up to a 20 true taper, all being thus gathered and shaped just ahead of the wrapper, and then as the wrapper is wound thereon it is gathered, all wrinkles are smoothed out and stretched and drawn smoothly over the surface of the 25 head and finished smooth by the continuous percussion of said movable section or packer and shaper and its compacting and smoothing action upon the head singly and upon the head and the wrapper together as the latter 30 is progressively wound thereon, such action being quick and incisive in order not to seriously stop or retard the rotation of the bunch, the primary action being to draw the head to a predetermined shape and size analogous to the drawing of a piece of metal in a 35 die. I also provide a nicker-knife mounted to be reciprocated longitudinally upon the vibratory arm which carries the reciprocating header-section, whereby said nicker is 40 brought forward into position to nick the wrapper by a succession of blows and is then retracted out of cutting position.

It is constructed as follows, reference being had to the accompanying drawings, in which—

45 Figure 1 is an end elevation of part of a cigar-bunch-rolling machine sufficient to show the present invention. Fig. 2 is a top plan thereof. Fig. 3 is a front elevation thereof. Fig. 4 is a sectional elevation showing the header open, the header-section raised, and the nicker retracted. Fig. 5 is a like

view showing the header open, the movable section lowered, and the nicker thrown forward into its operative position. Fig. 6 is an elevation looking into the header-cavity, 55 showing the reciprocating section raised. Fig. 7 is a like view showing the same lowered.

The bed 2, the frame 3, apron 4, pressure-roller 5, and wrapper-stretcher 6 are all old, being here shown only for illustration, as they can 60 be varied according to the style or class of any rolling-machine.

The paste-reservoir 7, conduit 8, valve-lever 9 and its cam accessories, draw-rod 10, finger-lever 11, stops 12 13, and retracting-spring 14 are not strictly part of this invention, but are the subject-matter of my separate application, filed December 2, 1897, Serial No. 660,467, for the pasting mechanism, and are here shown because the nicker is here 70 shown as connected to and advanced and retracted thereby; but it is evident that it can be thus advanced and retracted in many different ways.

The stationary section 15 of the header is 75 suitably mounted upon the bed and is provided with an interior recess of the proper shape for the head of the cigar to be rolled, and 16 is the movable or vibratory section, 80 concaved on lines concentric, or substantially so, with the recess in the stationary section.

Upon an upright 17, erected upon the bed, a vibratory arm 18 is suitably hung or mounted, as at 19, to which the movable section is secured. This arm is suitably prepared to 85 properly receive or be engaged by an eccentric 20 upon a shaft 21, suitably journaled in a bearing 22, erected upon said bed, which is driven by the pulley 23, belt 24, and drive-pulley 25 upon the shaft 26, which is driven 90 in any suitable manner. (Not here shown.) When the bed is a part of a traversing carriage, the drive-pulley is elongated according to the distance of such traverse. Upon the side of the arm 18 the nicker-knife 27 is 95 mounted by a slot and screw or pin joint 28, being thus free to be reciprocated. It is also suitably connected to a shifter-arm 29 upon a rock-shaft 30, provided with a crank 31, connected by a rod 32 to the valve-lever 9, 100 whereby when said finger-lever is pressed down the rod 32 is forced forward, rocking

- said shaft, swinging the arm 29 forward, which throws the nicker forward into operative position, and when said lever is released said spring operates to retract said nicker.
- 5 This nicker-shifting mechanism is here shown as operated by the pasting mechanism; but it is evident that the nicker can be reciprocated upon said vibratory arm in many other ways.
- It will be seen that as soon as the head of a 10 bunch is placed in the header and its rotation begins the movable section will be vertically vibrated, striking continuously a succession of percussive blows thereon, and thus imparting such blows to the head uniformly at all points 15 as it rotates, and thus by percussion continuously compacting, smoothing, and shaping said rotating head, and then as the winding of the wrapper reaches this smoothed and shaped head the movable section will exert 20 its percussive force continuously upon the wrapper to smooth it, removing all wrinkles, and cause it to be wound closely around the head, and at the same time prevents all twisting of either the filler, binder, or wrapper or 25 tearing of the wrapper and finishes the head properly. At the proper time the operator throws the nicker forward, and the wrapper is nicked by the succession of cuts made without being held at any one time long enough 30 to be torn. A groove or recess 33 in the bed permits the nicker to be vertically vibrated without damage when retracted.
- I do not limit myself to any particular direction of movement for the movable section.
- 35 It will be seen that it may also bear any desired ratio in size to that of the stationary section and that the percussive means are connected to and coöperate with the bunch-rolling mechanism and are not separate from or 40 operated independently of the cigar-forming or bunch-rolling mechanism, but are simultaneously operated therewith, and their propelling or operating power is continuously applied during the entire rotation of the bunch, 45 only stopping whenever the bunch ceases to be revolved.
- Having described my invention, what I claim, and desire to secure by Letters Patent, is—
- 50 1. In a cigar-bunch-rolling machine, a header comprising a stationary and a continuously-movable section, both recessed in- teriorly, combined with a bunch-rolling mechanism, and means to vibrate said movable section to automatically compact the rotating 55 bunch-head by percussion.
2. In a cigar-bunch-rolling machine, a header comprising a stationary and a continuously-vibrating section exerting a percussion force upon the head of a rotating 60 bunch in the stationary section, at an angle to its axis of rotation and means to vibrate said movable section to automatically compact it against the stationary section.
3. In a cigar-bunch-rolling machine, the 65 combination with a bunch-rolling mechanism, of an interiorly-recessed stationary header-section, a continuously-vibratory arm, and a header-section thereon acting percussively upon the head of a bunch in the stationary 70 section and means to vibrate said arm and movable section together.
4. In a cigar-bunch-rolling machine, the combination with a bunch-rolling mechanism, of an interiorly-recessed stationary header 75 having a portion cut away, and a continuously-operated vibratory bar playing through said cut-away portion to automatically deal a succession of blows continuously upon the head of a revolving bunch, and compact it against 80 the stationary section, and means to vibrate said bar.
5. In a cigar-bunch-rolling machine, the combination with a bunch-rolling mechanism, of a header open on one side interiorly re- 85 cesses, and a continuously and automatically vibrating striker whereby a continuous succession of blows is struck upon the head of a bunch rotating in said header, shaping it by percussion, and means to vibrate said striker. 90
6. In a cigar-bunch-rolling machine, the combination with a bunch-rolling mechanism, of a vibratory arm, and a nicker mounted thereon whereby a wrapper is automatically nicked by a succession of cuts made by said 95 nicker, and whereby the nick is cut upon a curved line.

In witness whereof I have hereunto set my hand this 22d day of November, 1897.

ROSS M. RUSSELL.

In presence of—
C. W. SMITH,
HOWARD P. DENISON.
